United States Patent Office.

OLIVER H. REED, OF WASHINGTON, DISTRICT OF COLUMBIA.

Letters Patent No. 77,527, dated May 5, 1868.

IMPROVEMENT IN GUIDE-GAUGES FOR PRINTING-PRESSES.

The Schedule referred to in these Letters Patent and making part of the same.

TO ALL WHOM IT MAY CONCERN:

Be it known that I, OLIVER H. REED, of Washington, in the county of Washington, and District of Columbia, have invented a new and useful Improvement in Printing-PresSES; and I do hereby declare that the following is a full and exact description thereof, reference being had to the accompanying drawings, and to the letters of reference marked thereon.

My invention consists of a folding side guide for paper as an improvement in printing-presSES.

In the accompanying drawings—

Figure 1 is a top view of my improvement.

Figure 2 is a side view of the same.

The plate A is to be inserted into the feed-board of Hoe's press, or attached to the guide-bar of a Gordon press by means of the thumb-screw B, fig. 2. Into the face of this plate is inserted a pin, C, secured by a pivot, D, and bearing against the plate-spring E on the under side of the plate A. By this arrangement the pin C may be folded down into a groove, G, and thus leave the face of the feed-board smooth or unobstructed when the pin is not in use. A small concavity, H, fig. 1, admits the finger for raising the pin.

Two or more of these pins may be used upon the same press, if desired, or the plate A may be reversible, or have a wide range of adjustability when necessary.

My improvement renders the pin or side guide a permanent part of the printing-press, and prevents the well-known difficulties of the common pin as a side guide, and of the more permanent yet removable pin sometimes used.

I do not confine my invention to the precise construction above described, as the form may be varied somewhat without departing from my invention.

Having thus fully described my invention, what I desire to secure by Letters Patent of the United States, is—

The use of a folding pin or side guide for paper upon a printing-press, substantially as set forth.

OLIVER H. REED.
